Patented Dec. 6, 1921.

FIG. 1

FIG. 2

FIG. 3

Inventor
Otto Meyer.
By Munro Co.
Atty's.

UNITED STATES PATENT OFFICE.

OTTO MEYER, OF CHICAGO, ILLINOIS.

DRUM-EAR.

1,399,392.

Specification of Letters Patent.

Patented Dec. 6, 1921.

Application filed May 10, 1920. Serial No. 380,178.

To all whom it may concern:

Be it known that I, OTTO MEYER, a citizen of the United States, and a resident of Chicago, in the county of Cook and State 5 of Illinois, have invented a new and useful Improvement in Drum-Ears, of which the following is a full, clear, and exact description.

My invention relates to improvements in 10 drum ears, and it consists in the combination, constructions, and arrangements herein described and claimed.

An object of my invention is to provide 15 a drum ear which has means for preventing the slipping of the same along the drum cord or rope.

A further object of my invention is to provide a device of the type described that can be quickly adjusted and which will not 20 "stick" nor cut the drum cord or rope.

A further object of my invention is to provide a device of the type described that is relatively simple in construction and operation and which is not likely to get 25 out of order easily.

A further object of my invention is to provide a device of the type described that is thoroughly practical commercially.

Other objects and advantages will appear 30 in the following specification, and the novel features will be particularly pointed out in the appended claims.

My invention is illustrated in the accompanying drawings, forming part of this application, in which—

Figure 1 is a perspective view of the drum, showing the device applied,

Fig. 2 is a plan view of the drum ear,

Fig. 3 is a longitudinal section through 40 the drum ear, a pin that may be used there-with also being shown,

Fig. 4 is a section along the line 3—3 of Fig. 2.

It is well known that perfect vibration is 45 an absolute necessity to a good drum tone. To attain this object, it is necessary that the drum heads be adjusted and held under tension. The tension is ordinarily adjusted by means of drum ears which are disposed 50 upon the drum rope which is passed backwardly and forwardly between the drum hooks. It has been found that the drum ears in common use are unsatisfactory in that they slip along the rope, thereby re- 55 lieving the drum tension and preventing the attainment of perfect vibration. This

defect in the drum ears may be occasioned by the wearing of the surface thereof, which frictionally engages the drum rope or by the fact that the same is affected by weather 60 conditions. When my improved drum ear is used, slipping of the same along the rope is prevented while the drum ear may be instantly adjusted with respect to the rope to increase or lessen the tension on the drum 65 heads.

Referring now to Fig. 1, it will be noted that I show a drum having a head 1, a shell 2, counterhoops 3, and a drum cord 4, which is passed back and forth between the drum 70 hooks 5 which are disposed upon the counterhoops 3 in the ordinary manner. It is to be noted that the drum hooks 5 are arranged in staggered position with respect to each other. The parts described so far are 75 of ordinary construction and form no part of my invention except in so far as they co-operate with the parts about to be described.

I provide a drum ear having a body portion 7 to which a lug 6 preferably leather 80 is secured by means of a rivet 8 or by any other suitable means. The body portion 7 in the preferred form of the device consists of a flat metal member which has its side edges bent downwardly and then toward 85 each other, as best seen in Fig. 4. A portion of the leather lug 6 is inserted within the body portion 7 and is curved to conform with the shape of the latter, thus forming a lining for the body portion 7. The outer 90 end of the leather lug 6 is formed in a convenient shape to permit the same being grasped by hand when it is desired to move the drum ear along the drum cord 4.

The body portion 7 is formed with a slot 95 9 and with the extensions 10, as shown in the drawings. A rod-like member 11 has one end disposed within the slot 9 and is maintained therein by means of a pintle 12 which is inserted through registering openings in the extensions 10 and the rod-like member 11. The rod-like member 11 is fashioned with an upturned end 13, and is adapted to be swung about its pivot into a position at right angles to and between 100 adjacent portions of the drum cord, the outer end thereof then being in engagement with the drum shell 2, wherefore the drum ear is moved outwardly from the drum. A recess 14 is provided in the upturned end 110 13 for a purpose to be hereinafter set forth.

From the foregoing description of the

various parts of the device, the operation of the device may be readily understood. Adjacent portions of the drum rope 4 will be placed within the drum ear in the manner shown in Fig. 1 of the accompanying drawings. The cord or rope 4 will be held therein on account of the shape of the body portion 7 which serves as a guiding member. The portion of the leather lug 6 which 10 is inserted within the body portion 7 frictionally engages the drum cord 4 and tends to prevent the slipping of the device therealong. The rod-like member 11 which is pivoted on the pintle 12 has a diameter 15 greater than the distance between the adjacent portions of the drum cord 4 when such portions are received within the body portion 7. Consequently to positively prevent slipping of the device it is only necessary to move the free end of the pivoted member 11 downwardly between the adjacent portions of the drum cord 4, thus spreading the adjacent portions.

It will be obvious that the drum ear cannot slip while the pivoted member 11 is in the position indicated by the dotted line in Fig. 3, since the body portion 7 is positively maintained in position by tension exerted on both sides thereof by the adjacent portions of the drum rope which diverge on both sides thereof. The pivoted member 11 may be conveniently operated by grasping a pin 15 which has been inserted within the recess 14 of the end 13. It is, of course, 35 obvious that the pivoted member 11 may be operated in any suitable manner.

It is readily apparent that modifications

and adaptations of the form of the device pictured in the accompanying drawings may be provided without departing from the spirit and scope of my invention as set forth in the foregoing disclosure and outlined more particularly in the appended claims. I therefore consider such modifications and adaptations as my own. 45

I claim:

1. The combination in a drum of a drum ear having a body portion provided with a pair of extensions, a drum cord under tension passed and repassed through said drum ear, and a rod-like member mounted between said extensions for movement between adjacent portions of the drum cord and being adapted to then engage with said drum to cause said drum ear to be moved outwardly. 50

2. The combination in a drum with a drum cord under tension, of a drum ear, said drum ear having a body portion provided with a pair of extensions and a rod-like member pivoted therebetween, said pivoted member having a diameter greater than the normal distance between the adjacent parallel portions of said drum cord, having a length greater than the normal 65 distance between said drum ear and the adjacent portion of the drum, and being adapted to be swung about its pivot between adjacent portions of the drum cord, thereby spreading such adjacent portions apart 70 and moving the drum ear outwardly from the drum.

OTTO MEYER.
